UNITED STATES PATENT OFFICE

169,295

BUCKLE

Harold S. van Buren, Jr., Cambridge, Mass.

Application November 3, 1951, Serial No. 17,245

Term of patent 14 years

(Cl. D17—1)

To all whom it may concern:

Be it known that I, Harold S. van Buren, Jr., a citizen of the United States, residing at Cambridge, State of Massachusetts, have invented a new, original, and ornamental Design for a Buckle, of which the following is a specification, reference being had to the accompanying drawing, forming a part hereof.

Fig. 1 is a top plan view of a buckle embodying my new design;

Fig. 2 is a side elevational view of the buckle of Fig. 1 as seen from the lower edge;

Fig. 3 is an end elevational view of the buckle of Fig. 1 as seen from the right side; and

Fig. 4 is a view in section taken on line 4—4 of Fig. 1.

The characterizing features of the design are those shown in solid lines.

I claim:

The ornamental design for a buckle, as shown and described.

HAROLD S. VAN BUREN, JR.
